Des. 240,611
Patented July 20, 1976

240,611

COMBINED TACHOMETER, ADVANCE METER AND TIMING LIGHT

Edwin L. Schwartz, Los Angeles, Calif., assignor to
Rite Autotronics Corporation

Filed Nov. 18, 1974, Ser. No. 524,475

Term of patent 14 years

Int. Cl. D10—04

U.S. Cl. D10—78

Fig. 1.

Fig. 2.

Fig. 3.

Fig. 4.

Fig. 5.

FIG. 1 is a side elevational view of a combined tachometer, advance meter and timing light showing my new design;

FIG. 2 is a top plan view;

FIG. 3 is a bottom plan view;

FIG. 4 is a front elevational view; and

FIG. 5 is a rear elevational view.

I claim:

The ornamental design for a combined tachometer, advance meter, and timing light, substantially as shown.
